A. AMANN

INSTRUMENT STERILIZER

Filed Jan. 2, 1926.

Inventor:

Adolf Amann

By *Georg Munk*
Attorney

Patented Oct. 25, 1927.

UNITED STATES PATENT OFFICE.

ADOLF AMANN, OF SCHOMBERG, NEAR WILDBACH, GERMANY.

INSTRUMENT STERILIZER.

Application filed January 2, 1926, Serial No. 78,980, and in Germany August 24, 1925.

This invention relates to an apparatus for sterilizing chirurgical instruments by means of steam, and especially for sterilizing dentist's instruments and injection syringes. 5
 5 The apparatus consists of a portable vessel for the generation of steam, said vessel having a handle and feet, and a removable lid fitted with an inlet and a safety valve. On the conical top end of a tube fixed on the 10 lid an insertion tube is pressed by the action of a spiral spring, branch tubes branching off from said insertion tube. One of these branch tubes is horizontal and has a conical end, the other branch tube being curved in 15 upward direction and carrying a cylinder open at its upper end.

An embodiment of the invention is shown, by way of example, in the accompanying drawing, in the only figure of which the sterilizing apparatus is shown in longitudinal 20 section.

On a cylindrical vessel *c*, having a handle *a* and mounted on feet *b*, a lid *d* is placed. This lid *d* has a tubular inlet *d*¹ containing 25 a safety valve, and a tubular extension *e* at the centre. On this tubular extension *e* a vertical tube *f* is mounted. In a flange on the top end of tube *f* a rod *h* is guided which has two upwardly and outwardly extending arms *p* designed to grip over the 30 handle of the instrument to be sterilized, as for instance the casing *q* of an injection syringe. A spiral spring *g* wound around said rod *h* serves to pull the gripping arms downwards. From the lower portion of 35 tube *f* a horizontal tube *k* is branched the free end *l* of which is conical. A tube *m* branching off from tube *f* above said horizontal tube *k* is curved upward and carries 40 a cylinder *u* open at the top end. A cock *n* serves for shutting off the portion of tube *f* above said horizontal branch tube *k*. On the upper end of tube *f* a sleeve *o* is mounted which is designed to support the instrument 45 to be sterilized. The conical end *l* of the horizontal tube *k* is designed to receive for instance an injection needle *r*. The opening in the rounded end *l* of tube *k* is large enough to accommodate the fixing screw *s* of 50 an injection needle with sufficient play to prevent steam penetrating into the syringe

t. The branch tube *k* is horizontal so that no liquid contained in the cylinder of the syringe *t* can drop out of the needle *r*. The cylinder *u* on the curved tube *m* is designed to receive the piston *v* of a syringe. Other instruments to be sterilized are placed into a box which has a hole fitting on the rounded end *l* of the horizontal tube *k* but is not shown in the drawing.

The improved apparatus can be used for rapidly sterilizing the needle of an injection syringe during an operation and also for sterilizing the other parts of a syringe or other instruments as superheated steam has a much better sterilizing effect than any other means for instance than alcohol into which the articles to be sterilized are dipped. The cock permits of shutting off the upper portion of tube *f* and the elements mounted 70 on the same, or of throttling the steam according to request.

The vessel *c* can be heated in any convenient manner for instance by gas.

I claim:—

An apparatus for sterilizing chirurgical instruments, specially dentist's instruments and injection syringes, by means of steam comprising in combination with a steam generating boiler, a steam outlet in the top end 55 of said vessel, a vertical steam tube, a horizontal branch at the lower end of said vertical steam tube and having an opening in its end to hold the point of a syringe, a valve cock in said horizontal branch tube, a valve cock in said vertical steam tube above 60 said horizontal branch tube, an upwardly directed curved tube branching from said steam tube above said valve cock, an open cylinder on the open end of said curved 65 branch tube and designed to hold an element to be sterilized, a spring-controlled vertical rod shiftably mounted on the outer side of the upper portion of said vertical steam tube, two gripper arms extending from said 70 shiftable rod for gripping over the handle of an instrument to be sterilized to pull the same onto the open top end of said vertical steam tube.

In testimony whereof I affix my signature.

ADOLF AMANN.
